UNITED STATES PATENT OFFICE

168,095

TOOL DISPLAY STAND

Edgar F. Howard, Milwaukie, Oreg., assignor to
The Plomb Tool Company, Los Angeles, Calif.,
a corporation of California

Application July 5, 1952, Serial No. 20,479

Term of patent 14 years

(Cl. D80—9)

To all whom it may concern:

Be it known that I, Edgar F. Howard, a citizen of the United States of America, residing in the city of Milwaukie, county of Clackamas, State of Oregon, have invented a new, original, and ornamental Design for a Tool Display Stand, of which the following is a specification, reference being had to the accompanying drawing forming a part thereof.

Figure 1 is a perspective view of a tool display stand showing my new design;

Figure 2 is a view similar to Figure 1, but showing the display stand in another aspect;

Figure 3 is an elevational view showing the display stand in still another aspect; and

Figure 4 is a plan view taken as indicated by the arrows 4—4 of Fig. 2.

I claim:

The ornamental design for a tool display stand, substantially as shown.

EDGAR F. HOWARD.
